UNITED STATES PATENT OFFICE.

WALTER P. MURPHY, OF NEW YORK, N. Y., ASSIGNOR TO P. H. MURPHY COMPANY, OF PARNASSUS, PENNSYLVANIA, A CORPORATION OF PENNSYLVANIA.

CAR-ROOF.

1,360,562.

Specification of Letters Patent. Patented Nov. 30, 1920.

Application filed May 24, 1920. Serial No. 383,784.

To all whom it may concern:

Be it known that I, WALTER P. MURPHY, a citizen of the United States, and a resident of the city of New York, in the county 5 of New York and State of New York, have invented new and useful Improvements in Car-Roofs, of which the following is a specification.

This invention relates to outside metal 10 car roofs of the type shown in C. C. Murphy Patent No. 1,133,493, dated March 30, 1915, wherein the roof sheets are pivotally mounted near the ridge on the substructure and are arranged between mullions or bat- 15 tens that are disposed crosswise of the car, the mullions and the flanges of the adjacent sheets on opposite sides thereof being covered by seam covers.

The principal object of the present in- 20 vention is to provide a simple arrangement which will permit a greater movement of the sheets at the eaves of the car than at the ridge when the car is thrown out of square without danger of the sheets or seam 25 covers striking the mullions and becoming damaged and without requiring sheets or seam covers of special shape. Another ob- 30 ject is to provide an end construction for the roof which will permit the end seam cover to shift to accommodate itself to the greater movement of the end sheet at the eaves end of the car than at the ridge, and at the same time maintain a water-tight 35 joint between the end sheets and the end seam cover.

The invention consists in the arrange- 40 ment for obtaining a greater space between the side margins of the sheets and the mullions at the eaves than at the ridge to per- mit a greater movement of said sheets at the eaves than at the ridge; and it further 45 consists of the parts and in the arrangements and combinations of parts herein- after described and claimed.

In the accompanying drawings, which 45 form part of this specification, and wherein

like symbols refer to like parts wherever they occur,

Figure 1 is a top plan view of the end portion of the car roof embodying the invention, parts being shown removed or broken away to more clearly illustrate the invention;

Fig. 2 is an enlarged vertical cross-section through one of the transverse seams, 55 the section being taken near the ridge on the line 2-2 in Fig. 1;

Fig. 3 is a vertical cross-section taken through the seam near the eaves, the section being taken on the line 3-3 in Fig. 1; 60

Fig. 4 is a vertical cross-section taken through the end of the seam, the section being taken near the eaves on the line 4-4 in Fig. 1;

Fig. 5 is a section similar to Fig. 4 showing the modified form of end seam construction; and 65

Fig. 6 is a vertical cross-section of the eaves of the roof, the section being taken adjacent to a transverse seam on the line 6-6 in Fig. 1.

Referring to the drawings, the invention is illustrated as applied to a car comprising side sheathing 9, roof sheathing 10 supported at the eaves on side plates 11 and 75 at the ridge by means of a ridge pole 12. Battens or mullions 13 extend crosswise of the car from ridge to eaves, those on one side of the ridge being in alinement with those on the opposite side respectively. 80 These mullions, which are bolted or otherwise secured on top of the roof sheathing 10 are spaced apart longitudinally of the car, and in the spaces between adjacent mullions are arranged rectangular metal 85 roof sheets 14.

The metal roof sheets 14 are arranged end to end in pairs, the sheets of each pair being on opposite sides of the ridge and being spaced apart at the ridge and extending 90 to the eaves portion of the car. Each pair of oppositely disposed roof sheets is pivotally

mounted on the roof substructure by means of a sheet metal anchor plate 15 which straddles the ridge of the roof and has upstanding bosses 16 formed therein, which 5 project into similar bosses 17 formed in the roof sheets near their ridge ends. The eaves ends of the roof sheets are movably secured to the substructure by means of angle flashing strips 18. These flashing strips 10 rest in a rabbet formed in the eaves ends of the roof sheathing and extend from end to end of the car, passing beneath the mullions. The vertical flange of the flashing strip is nailed or otherwise secured to the 15 side of the car and the portion resting in the rabbet is doubled back upon itself, as at 19, and the eaves ends of the roof sheets are doubled under, as at 20, and hooked into the doubled-back portion of the flashing strip. 20 The side and ridge margins of the roof sheets are flanged up and turned in and down forming hooked flanges 21 and 22. The side margins of the roof sheets adjacent to the mullions 13 are covered by trans- 25 verse seam covers 25. The transverse seam covers 25 are of an inverted channel shape. These seam covers straddle the mullions 13 and the side margins of adjacent sheets and have flanges 26 which extend inwardly and 30 upwardly from the lower side margins of said seam covers, said flanges 26 being adapted to interlock with the hooked flanges 21 formed on the side margins of the roof sheets. The eaves ends 27 of the top portion 35 of the transverse seam covers are bent down over the eaves ends of the mullions 13 and then turned under the adjacent flanges 20 of the roof sheets located on each side of the mullions. The top portions of the trans- 40 verse seam covers lap at the ridge (not shown) and are perforated to receive saddle bolts 29 of running board saddles 30.

Inverted channel shaped ridge seam covers 23, which are similar in cross-section to 45 the transverse seam covers 25, straddle the ridge margins of each of the adjacent curved roof sheets, and have their lower margins flanged inwardly and upwardly to form hooked flanges (not shown) which interlock with the hooked flanges 22 at the ridge 50 margins of each sheet.

The adjacent ends of the ridge seam covers 23 and the ridge ends of the transverse seam covers 25 are covered by the usual 55 four way center or corner caps 31, each of which has an opening in each of its four walls to receive the ends of the ridge and transverse seam covers. The center caps have center holes in their top walls through 60 which the saddle bolts 29 pass.

Running boards 34 are secured to running board saddles 30, which rest on the transverse seam covers 25 and are supported on the mullions 13 arranged beneath 65 said seam covers, thus permitting movement

of the sheets and the transverse seam covers. The running board saddles 30 are secured to the substructure by the saddle bolts 29 which extend through the roof sheathing and ridge pole. 70

The bosses 17 in the roof sheets are held down on the bosses 16 in the anchor plate 15 by means of intermediate running board saddles or anchor saddles 36, which have their under sides shaped to fit the pitch of 75 the roof and provided with circular recesses adapted to fit over the bosses 17 of the roof sheets. The anchor saddles 36 straddle the ridge seam covers and are secured to the substructure by bolts 38 which 80 extend downwardly through the tops of the ridge seam covers, anchor plates, roof sheathing and ridge pole.

The mullions 13 taper in width from the ridge portion of the roof toward the 85 eaves so that the space between the side margin of a sheet and the adjacent side face of the adjacent mullion increases toward the eaves. This arrangement permits a greater amount of movement of both the 90 sheets and the seam covers at the eaves than at the ridge. Thus, when the car frame is distorted, the sheets tend to turn on their pivots near the ridge and accommodate themselves to the distorted shapes of the 95 spaces between mullions; and their capacity for accommodating themselves to such distortion is increased by the greater clearance furnished at the eaves by the tapering of the mullions. The taper of the mullions 100 is such that, when the distortion of the car approaches a maximum, there is substantially no clearance between the mullion and the sheet throughout the length of the sheet; so that the body of the mullion, notwithstanding its taper, is sufficient to prevent the 105 seam cover from being crushed by the trainmen.

As shown in Fig. 4, the end transverse seam covers 39 rest on the end mullions 13^a 110 and have their outer margins bent down and rigidly secured to the end of the car. For this reason, the end seam covers do not interlock with the adjacent side flanges 21 of the end sheets, but are merely turned down inside of the pans of the end sheets and provided with base flanges 40, which rest on the body portions of the sheets within the side flanges thereof. A special end corner cap 50 is used to cover the ridge ends 120 of the end seam covers 39 and the adjacent ends of the end ridge seam covers.

In Fig. 5, a modified form of under seam construction is shown. In this figure, the end mullion 13^b is shown spaced back a suitable distance from the end of the car and is covered by channel shaped end seam covers 41 similar to the intermediate seam covers 25. The inner hooked flanges of the end seam covers 41 interlock with the adjacent 130

hook flanges 21 of the end sheets and the outer hooked flanges engage the upper surface of the web portion of Z-shaped flashing strips 42. The outer depending flanges 5 of the flashing strips 42 are secured to the end of the car and the inner flanges project upwardly alongside of the outer side faces of the end mullions. The flashings 42 and the outer portion of the end seam covers 10 are covered by end caps 43 of angle section, the vertical flanges of which are secured to the end of the car and the inwardly projecting top flanges extend over the flashings 42 and end seam covers 41. This arrangement permits movement of the end seam covers 41 and provides a weather-proof seam construction for the end of the car.

What I claim is:

1. A car roof comprising a substructure 20 divided into a plurality of spaces extending crosswise of the car, roof sheets movably arranged in said spaces, said spaces being wider at the eaves than at the ridge to permit greater movement of the sheets at the 25 eaves than at the ridge.

2. A car roof comprising a sheathing divided ridgewise and crosswise of the car into a plurality of spaces, and rectangular roof sheets movably arranged in said spaces and 30 pivotally connected to the roof sheathing and the roof substructure adjacent to the ridge, water-proofing means for the adjacent margins of said roof sheets, said spaces being wider at the eaves than at the ridge to permit a greater swinging movement of the sheets at the eaves than at the 35 ridge.

3. In a car roof, a substructure comprising members extending crosswise of the car 40 and spaced apart to form a plurality of spaces, and roof sheets movably arranged in said spaces, said spaces being wider at the eaves than at the ridge to permit greater movement of the sheets at the eaves than at the ridge.

4. In a car roof, a substructure comprising members extending crosswise of the car and spaced apart to form a plurality of spaces, roof sheets movably arranged in said 50 spaces, said members tapering in width from the ridge toward the eaves to form spaces therebetween which are wider at the eaves than at the ridge, thereby permitting a greater movement of the sheets at the eaves than at the ridge.

5. In a car roof having a substructure comprising members extending crosswise of the car and spaced apart longitudinally thereof to form a plurality of spaces, roof 60 sheets arranged in said spaces and pivotally secured to the substructure near the ridge, seam covers supported by the cross members and loosely engaging the side margins of adjacent sheets, said cross members tapering in width from the ridge toward the

eaves whereby the spaces therebetween are wider at the eaves than at the ridge thereby permitting greater movement of the sheets at the eaves than at the ridge.

6. A car roof comprising sheathing, mullions extending crosswise of said sheathing and spaced apart longitudinally thereof to form a plurality of spaces, roof sheets movably arranged in said spaces on opposite sides of the ridge, ridge seam covers movably connecting the ridge ends of said sheets, and movable transverse seam covers spanning said mullions and loosely connecting the side margins of adjacent sheets, the spaces between said mullions being greater 70 at the eaves than at the ridge thereby permitting a greater movement of the sheets between mullions at the eaves than at the ridge.

7. A car roof comprising sheathing, mullions extending crosswise of the car on top of said sheathing and spaced apart longitudinally thereof to form a plurality of spaces, roof sheets loosely arranged in said spaces on opposite sides of the ridge and 80 pivotally secured to the roof substructure near their ridge ends, ridge seam covers movably connecting the ridge ends of said sheets, and movable transverse seam covers spanning said mullions and loosely connecting 85 the side margins of adjacent sheets, said mullions being wider at the ridge than at the face whereby the spaces therebetween are wider at the eaves than at the ridge and thereby permit greater movement of said 90 sheets and said transverse seam covers at the eaves than at the ridge.

8. An outside metal car roof comprising mullions extending crosswise of the car and spaced apart lengthwise thereof to form a plurality of spaces, roof sheets movably arranged in said spaces on opposite sides of the ridge, seam covers loosely connecting the ridge ends of said sheets, seam covers spanning the mullions and loosely connecting 105 the side margins of adjacent sheets, said mullions tapering in width from the ridge toward the eaves whereby the spaces therebetween are wider at the eaves than at the ridge to permit a greater movement of the sheets at the eaves than at the ridge, an end cap secured to the end of the car and lapping the endmost seam cap and mullion, and a flashing strip disposed beneath the end seam cover and said end cap, said flashing strip being secured to the car end and having a portion extending inwardly beneath the end seam cover and turned upwardly along the side of the end mullion.

9. An outside metal car roof comprising 115 mullions extending crosswise of the car and spaced apart lengthwise thereof to form a plurality of spaces, roof sheets loosely arranged in said spaces on opposite sides of the ridge, seam covers loosely connecting 120

the ridge ends of said sheets, seam covers spanning the mullions and loosely connecting the side margins of adjacent sheets, said mullions tapering in width from the ridge 5 toward the eaves whereby the spaces therebetween are wider at the eaves than at the ridge to permit a greater movement of the sheets at the eaves than at the ridge, and

an end cap rigidly secured to the end of the car, said cap having a portion extending over the end mullion and being turned down over the adjacent side margin of the end sheet. 10

Signed at Chicago, Illinois, this 20th day of May, 1920.

WALTER P. MURPHY.
